CLAIM

I claim the ornamental design for a toothbrush bristle arrangement, as shown and described.

DESCRIPTION

FIG. 1 is a front perspective view of a toothbrush bristle arrangement showing my design;

FIG. 2 is a front view thereof;

FIG. 3 is a rear view thereof;

FIG. 4 is a left side view thereof;

FIG. 5 is a right side view thereof;

FIG. 6 is a top elevational view thereof;

FIG. 7 is a bottom elevational view thereof;

FIG. 8 is an enlarged partial view of FIG. 4; and,

FIG. 9 is an enlarged partial view of FIG. 2.

The dash-dash broken lines are included for the purpose of illustrating environment of the toothbrush bristle arrangement that forms no part of the claimed design. The dot-dash broken lines seen in FIGS. 2, 4, 8, and 9 are for the purpose of depicting enlarged view indicators, and form no part of the claimed design.
